CARD HOLDER

Joseph Octave Le Blanc, Hastings, Nebr.

Application April 12, 1934, Serial No. 720,310

9 Claims. (Cl. 40—11)

This invention relates to card holders and has for an important object thereof the provision of a holder whereby a card or other relatively thin member may be releasably held on a suitable support.

Another object of this invention is to provide a holder of this type whereby the article held thereby can be easily and quickly released by rocking an end of the holder so as to move the 10 clamping portion of the holder away from the support.

This invention is an improvement over the structure embodied in my application, Serial No. 712,824, filed February 24, 1934, for Card 15 holders.

The above and various other objects and advantages of this invention will in part be described and in part be understood from the following detailed description of the present preferred embodiment, the same being illustrated in the accompanying drawing wherein:—

Figure 1 is a detail front elevation of a device constructed according to the preferred embodiment of this invention.

Figure 2 is a detail side elevation of the device showing in dotted lines the released position of the device.

Figure 3 is a detail side elevation partly in section of the holder removed from a support.

Figure 4 is a detail side elevation of a modified form of this holder.

Referring to the drawing wherein like characters of reference designate corresponding parts throughout the several views, the letter B designates generally a base or support of suitable structure which may be either in a horizontal or vertical position, and the numeral 10 designates generally the body of an article clamping member which, as shown in Figure 3, is longitudinally bowed so that the opposite ends of the clamp or holder 10 will be in outstanding position to the face of the base or support B. The clamping member 10 at a point adjacent each end is provided with apertures 13 which are preferably elongated, and screws or securing members 11 are adapted to engage in the apertures 13 and the base B. These headed securing members 11 tension the body or clamping member 10 against the face of the base B and preferably, the screws 45 11 are so mounted as to permit slight longitudinal movement of the clamping member 10, as will be hereinafter described.

The clamping member 10 is provided at each end thereof with a releasing lever 12 which is outwardly offset from the clamping portion or body

10 so that when the device is in applied position, the releasing levers 12 will be spaced from the confronting face of the base B. The holder 10 is constructed of metal having an inherent resiliency and the inner end of each lever 12 is connected to the adjacent end of the body 10 by means of a curved portion 14 which acts as a fulcrum on which the lever 12 is rocked.

In Figure 4, there is disclosed a modified form of this holder mounted on a base B' and the holder here disclosed is constructed of an elongated strip of metal 10' provided with a bowed portion 15 at a point inwardly from the attaching screw 16. The strip 10' adjacent the other end is provided with a reversely bowed portion 17 and the end of the strip 10' is secured as by a securing member 18 to the base B'. A releasing lever 12' is integral with the strip 10' and a fulcrum 14 is formed at the point of connection between the lever 12' and the adjacent end of the strip 10'. In this modified form shown in Figure 4, the bowed portion 15 is uppermost and provides a means whereby the article in the form of a card or the like may be readily inserted between the base B' and the bowed portion 17. This bowed portion 15 is tensioned by the attaching member 16 so that the desired tension may be placed on the strip 10' and, in like manner, the screw 18 also acts to tension the opposite or lower end of the strip.

In the use of the holder shown in Figures 1, 2 and 3, when it is desired to insert an article between the clamping member 10, a lever 12 is pressed inwardly toward the base B, which action will cause the clamping member 10 to be moved into a position spaced away from the adjacent face of the base B and in this position, one or more cards may be easily inserted between the inner face of the strip 10 and the outer face of the base B. When the lever 12 is released, the inherent resiliency in the strip 10 will yieldably clamp the article onto the base B.

In the disclosure shown in Figure 4, the article is inserted between the strip 10' and the base B' without pressing the lever 12' inwardly or toward the base as the outwardly bowed portion 15 permits the insertion of the article between the strip 10' and the base B', and after the article has been inserted between this bowed portion 15 and the base B', it is moved downwardly toward the 50 clamping portion 17. When it is desired to release the article secured by the clamping strip 10', the lever 12' is pressed inwardly toward the base B', which movement will rock the lower end of the strip 10' on the fulcrum 14' and move the 55

lower end of the strip 10' away from the base B'.
What is claimed is:—

1. As a new article of manufacture, a holder for holding a flat object against a plane surface, comprising an elongated flat resilient strip bowed longitudinally, said strip having an opening adjacent each end, and an outwardly offset releasing lever integral with an end of the strip.
2. As a new article of manufacture, a holder adapted to be secured to a plane surface, comprising an elongated flat resilient strip bowed longitudinally and having an opening adjacent each end, threaded attaching and tensioning members passing through said openings to mount the strip on the plane surface, and an outwardly offset lever integral with an end of the strip.
3. As a new article of manufacture, a means for holding an article on a plane surface, comprising an elongated flat resilient strip bowed longitudinally and having an opening adjacent each end, means engaging in the openings for tensioning said strip, and a pair of outwardly offset levers carried one by each end of the strip, either of said levers upon movement thereof toward the plane surface raising the strip between the tensioning means and away from the plane surface to release articles placed between the strip and the plane surface.
4. As a new article of manufacture, a means for holding an article on a plane surface, comprising an elongated flat resilient strip having a bowed portion adjacent one end and a reversely bowed portion adjacent the other end, said strip having openings one adjacent each end, threaded attaching members passing through the openings, one of said attaching members constituting a means for tensioning the strip, and a lever integral with one end of the strip and offset therefrom whereby to raise the intermediate portion of the strip out of contact with the plane surface upon rocking of the lever inwardly toward the plane surface.
5. As a new article of manufacture, a card holding means comprising a member having a flat surface, an elongated resilient strip bowed longitudinally and having an opening adjacent

each end, attaching members passing through said openings and engaging the member for holding and tensioning the strip on the member, and a releasing lever integral with an end of the strip and offset outwardly from the face of the member. 5

6. As a new article of manufacture, a card holding means comprising a member having a flat surface, an elongated resilient strip bowed longitudinally and having an opening adjacent each end, attaching members passing through said 10 openings and engaging the member for holding and tensioning the strip on the member, and a pair of outwardly offset releasing levers one at each end of the strip.

7. As a new article of manufacture, a card 15 holding means comprising a member having a flat surface, an elongated resilient strip having a pair of bowed portions intermediate the ends thereof, one bowed portion being reverse from the other, said strip having an opening adjacent 20 each end, attaching members passing through said openings, and engaging the member for holding and tensioning the strip on the member, and a releasing lever integral with an end of the strip and outwardly offset from the face of the 25 member.

8. As a new article of manufacture, a holder adapted to be secured to a plane surface comprising an elongated flat strip having a pair of bowed 30 portions between the ends thereof and provided with an opening adjacent each end, threaded attaching and tensioning members passing through said openings to mount the strip on the plane surface, and an outwardly offset lever integral with an end of the strip. 35

9. As a new article of manufacture, a holder adapted to be secured to a plane surface, comprising an elongated flat resilient strip bowed longitudinally and having an opening adjacent each end, threaded attaching and tensioning 40 members passing through said openings to mount the strip on a plane surface, and a pair of outwardly offset levers integral one with each end of the strip. 40
